UNITED STATES PATENT OFFICE.

JOHN FEENEY, OF LODI, NEW JERSEY.

WINDOW SCREEN.

Application filed November 23, 1921, Serial No. 517,238. Renewed August 28, 1924.

To all whom it may concern:

Be it known that I, JOHN FEENEY, a citizen of the United States, residing at Lodi, in the county of Bergen and State of New Jersey, have invented certain new and useful Improvements in Window Screens, of which the following is a specification.

This invention has relation to window screens, and has for an object to provide a screen which is composed preferably of textile fabric, and a novel means for mounting the fabric over a window opening so that the fabric may be raised or lowered to cover any portion of the window opening exposed when any one of the sashes is raised or lowered.

Another object of the invention is to provide a window screen construction of the character above set forth embodying a spring roller mounted above the window casing, a pair of guide rods, one to be positioned at each side of the window casing, and a section of textile fabric wound partly around the roller and having means connecting the edges of said sections with the rod so that the fabrics may be readily raised or lowered to cover any portion of the window opening and securely held in such position.

In addition to the foregoing this invention comprehends improvements in the details of construction and arrangement on parts to be hereinafter described and particularly set forth in the appended claim.

In the accompanying drawings in which similar and corresponding parts are designated by the same characters of reference throughout the several views in which they appear:

Figure 1 is a view in front elevation of a window casing and sashes, illustrating the association therewith of my invention.

Figure 2 is a view in vertical section of the window casing and associated parts.

Figure 3 is a view in section similar to Figure 2 showing the upper portion thereof and the manner in which the screen is used to cover the upper portion of the window opening.

Figure 4 is a view in section of the window casing illustrating the screen in a fully lowered position.

Figure 5 is a detailed view on an enlarged scale in elevation of the guide rod for the screen.

Figure 6 is a detailed view in vertical section of the lower portion of the window casing and guide rod on an enlarged scale. 55

Figure 7 is a detailed view of the upper end of one of the guide rods.

Figure 8 is a detailed view in section of a fastening device for holding the guide rods, and 60

Figure 9 is a detailed view in section of a fastener for securing the screen in lowered position. 65

With reference to the drawings, 10 indicates the guide members of a window casing and 11 the window sill. The upper and lower sashes are indicated at 12 and 13 respectively, and an ordinary type of window shade and roller is indicated at 14. Mounted in the upper portion of the window casing below the roller 14 is a pair of window brackets 15, one at each side between which to support a shade roller 16. 70 Wound around said roller is one end of a piece of textile fabric indicated at 17, such as cheese cloth, crinoline or the like. Mounted on each side of the window casing is a vertical rod 18. The lower end of each rod is mounted upon a U-shaped bracket 19, which is designed to embrace the ends of the window sill 11. A set screw 20 is fixed to each clamp 19 to engage the under side of the sill and thereby hold the clamps in 80 place. Sleeves 21 are secured to the rear face of the screen 17 at the side edges, each sleeve being adapted to receive one of the rods 18. A nut 22 applied to the upper end of the rod prevents the sleeve from 85 being drawn outward therefrom. In this manner the screen is guided in vertical movement and held at its edges against the window casing. The sleeves 21 are held to the screen by means of strips of fabric 23 90

as shown in Figures 5 and 6. A rod 24 is extended transversely of the screen and located in a pocket formed therein against the lower end of the screen but leaving a flap 25 between the extremity of the screen and said rod 24. Another rod 26 is enclosed in a pocket formed upon the extremity of the flap 25, said rod 26 being shorter than the rod 24, it being noted that the flap 25 is provided with inturned edges 25a as 105 shown by Figure 5 of the drawings. Mounted on each side of the window casing is a plate 27, having a slot 28 formed therein

through which a pin, screw or the like, 29 extends, said screw penetrating the window casing to hold the plate thereto. A pin 30 extends from one end of the plate and embracing said pin is a sleeve 31. A button 32 having a center opening is slipped over the pin. Said opening is countersunk to provide a recess 33 in which a spring 34 is enclosed, said spring being embraced about 10 the pin and bearing at one end against the front and at its other end against the head 35 of the pin 30. The buttons 32 are designed to engage over the rod 18 to hold the same against the sides of the window casing so as to prevent the formation of a space between the edges of the screen and the window casing.

In use, the flap 25 of the screen is grasped and the latter raised or lowered after the 20 manner of a window shade so as to cover any portion of the window opening desired. When both of the sashes 12 and 13 are lowered every portion of the window may be covered, and the space between the lower 25 edge of the screen and the upper edges of the sashes may be closed by resting the rod 26 upon said sashes, the flap 25 closing said space to prevent the entrance of insects into the room. This is illustrated in Figure 3. 30 When the screen is in a fully lowered position as shown in Figure 4 it is held by means of a pair of nut fasteners 36, located upon the sill, these being mounted upon a pin 37 which enters a sleeve 38 on said sill, as 35 shown in Figure 9.

While I have illustrated and described my

invention with some degree of particularity, I realize that in practice various alterations therein may be made. I therefore reserve the right and privilege of changing the 40 form of the details of construction or otherwise altering the arrangement of the correlated parts without departing from the spirit of the invention or the scope of the appended claim.

Having thus described my invention, what I claim as new, and desire to secure by United States Letters Patent is:—

In combination with a window casing, a shade roller mounted thereon, a screen comprising a section of textile fabric wrapped at one end around the roller, a pair of rods 50 detachably connected to the sides of the casing including means for clamping the lower ends of the rods to the sill of said casing, a sliding sleeve on each of the rods, strips for attaching the fabric to the sleeves, a pocket formed in the lower portion of the fabric, a horizontal rod within the pocket, a second pocket in the extreme lower end of 60 the fabric, a rod within the last mentioned pocket, said fabric being turned inwardly on itself at the edges and between the rod to constitute flaps to be gripped in raising and lowering the screen.

In testimony whereof I affix my signature in presence of two witnesses.

JOHN FEENEY. [L. S.]
